UNITED STATES PATENT OFFICE.

AUGUST BENTKAMP, OF NEW YORK, N. Y.

POMPON.

Application filed June 3, 1923. Serial No. 525,614.

To all whom it may concern:

Be it known that I, AUGUST BENTKAMP, a citizen of the United States, residing at New York, in the county of New York and State of New York, have invented new and useful Improvements in Pompoms, of which the following is a specification.

This invention relates to pompoms or like ornaments and has for its primary object the provision of a device of this character constructed so as to greatly reduce the cost of manufacture of such devices while simplifying the method and operation of assembling the components thereof, and for giving to the completed device, a symmetrical form and a relatively fixed arrangement of components that will render the device extremely ornamental, strong and durable.

With the above and other objects in view which will appear as the nature of the invention is better understood, the same consists in the improved construction and novel arrangements of parts which will hereinafter be fully described and particularly pointed out in the claims.

In the accompanying drawing, has been illustrated, a single and preferred form of the invention, it being however, understood that no limitations are necessarily made to the precise structural details therein exhibited, but that changes, alterations and modifications within the scope of the claims may be resorted to when desired.

Figure 1, is a plan view illustrating a section of the foundation braid.

Figure 2, is a diagrammatic illustration showing the manner of folding the braid to form the foundation.

Figure 3, is a perspective view of the foundation.

Figure 4, is a side view of the complete pompon.

In carrying the invention into practice, I make use of a strip of braid 5, the same consisting of a medial knit mesh 6, having parallel rows of loops 7, in which are interwoven, the bristles or fibers 8. As shown in Figure 1, the fibers are arranged in parallel rows. This braid constitutes the foundation member of the invention and in order to complete the foundation, I fold a short section of the braid in a sinuous manner as shown in Figure 2. A strip of stem forming wire is then extended along the medial point of the braid or between the respective rows of bristles and by looping the wire and bind-

ing one end around the other, as shown in Figure 2, the foundation member is given a substantially fixed symmetrical form wherein the bristles or fibers 8 will be relatively free for a purpose to be hereinafter explained. The fibers 8 are preferably formed of a viscous substance such as gelatine. However, I do not wish to limit myself in this respect. The purpose of this arrangement will be fully referred to presently.

After I have given to the foundation member the ball-like form shown in Figure 3, I complete the pompon by associating with the foundation member a tuft of feathers or the like 9. The feathers of the tuft are individually inserted in the foundation member and the inner extremity of the feather is first dipped into a liquid adhesive and then inserted in the foundation member so as to adhere to the adjacent bristles 8. In some cases I insert the bristles singly while in others, I find it expedient to insert them in bunch formation in the foundation. In either case, I am able to give to the complete pompon, a highly ornamental appearance, while lessening the cost of manufacture of the device. The formation of the device is such that the operation of putting together the several components thereof, is greatly simplified and the device can be manufactured with maximum dispatch.

While I have primarily stated that the invention is intended for use in the art of millinery, I of course do not wish to be limited in this respect. The structure is designed whereby it may be made into the form of feather dusters or similar devices.

What is claimed as new is:—

1. A pompon comprising a foundation member consisting of a bristle-like structure, and a finishing tuft of feathers or the like secured to the bristles of said structure.

2. A pompon comprising a foundation member formed of a single strip of braid, said braid embodying closely associated bristles or fibers, the braid being folded on itself and provided with means to give to the foundation, a permanent form, and a tuft of feathers or the like secured to said fibers or bristles.

3. A pompon comprising a foundation member having closely associated viscous fibers or bristles, and a tuft of feathers or the like secured to said fibers or bristles.

4. A pompon comprising a foundation member consisting of a bristle like structure

arranged in strip form with the bristles separated into parallel rows, said material folded on itself and the folds being bound together so that the strip assumes a relatively permanent symmetrical formation, and a finishing tuft of feathers or the like secured by an adhesive to said bristles.

5. A device of the character described, comprising a flexible stem, a foundation member formed from a flexible strip of material provided with parallel rows of bristles, the stem being associated medially of

the strip of material and associated therewith so as to bind the folds of the strip together and a tuft of feathers secured by an adhesive to said bristles. 15

6. A device of the character described comprising a cluster of bristles, means for holding said cluster of bristles in a fixed form, and a tuft of feathers or the like secured by an adhesive to said bristles. 20

In testimony whereof I have affixed my signature.

AUGUST BENTKAMP.
